WAVE LENGTH MODULATION

Murray G. Crosby, Riverhead, N. Y., assignor to
 Radio Corporation of America, a corporation of
 Delaware

Application May 8, 1941, Serial No. 392,421

2 Claims. (Cl. 179—171.5)

This application concerns a new and improved wave length modulator of the type disclosed in my United States applications Serial No. 209,919, filed May 25, 1938, now U. S. Patent No. 2,250,095, dated July 22, 1941, Serial No. 311,047, filed December 27, 1939, and Serial No. 312,446, filed January 5, 1940, now U. S. Patent No. 2,279,660, dated April 14, 1942. In systems of this type push-pull reactance tubes are used to frequency modulate the tuning of an oscillator or phase modulate the tuning of an amplifier in accordance with modulating potentials which have or have not been subjected to preemphasis or relative amplitude correction in a desired manner. The new principle disclosed here is the use of like feedback phase shifters for the two reactance tubes. The reactive effects of the two tubes are made opposite by feeding the phase shifters from opposite sides of the tuned circuit. The use of like phase shifting in the circuits of the reactance tubes and wave generator simplifies arrangement, tuning, and adjustment thereof.

This type of modulator has all of the advantages which are obtained by push-pull reactance-tube modulators. These advantages include elimination of reaction from element voltage variations, increased linearity of modulation, and increased range of modulation. In addition, the present modulator has the advantage that the balance of the reactance tubes is more easily obtained. This ease of balance is obtained by the fact that, for some circuits, identical phase shifters may be used, while for other circuits the relative adjustments of the phase shifters is quite simple.

In describing my invention in detail reference will be made to the attached drawings: Figure 1 illustrates the essential elements of a wave length modulator using a pair of reactance tubes with similar phase shifting circuits; Figure 1a is a modification of the arrangement of Figure 1; while Figures 2, 3 and 4 are modifications of the arrangements of the prior figures.

The circuit of Figure 1 shows an embodiment using the principle of this invention. The principle concerns the manner of obtaining the phase shifted voltage which is fed back to the grids of the reactance tubes. In this arrangement 4 is the oscillator tube and 6 and 8 are the reactance tubes. The oscillator includes a tuned circuit 10 connected at one end to the anode 12 of tube 4 and at the other end to the grid 14 by way of a coupling and blocking condenser CB. Bias is supplied by resistance 16. The cathode 18 is coupled to a point on the inductance of 10,

Note that this point is closer to the grid end of circuit 10 than to the anode end thereof. The anodes 20 and 22 of tubes 6 and 8 are coupled to one end of circuit 10. Grids 24 and 26 of tubes 6 and 8 are coupled by condensers and reactance combinations C and R and C' and R' to the ends of circuit 10. CgK and CgK' represent the grid to cathode capacity of tubes 6 and 8 respectively and are taken into consideration in deriving the phase quadrature voltages on the anodes and grids of tubes 6 and 8. Bias is supplied to the grids 24 and 26 by resistances 28 and 30 and 32 and 30. Modulating potentials are applied by a transformer T to the grids 34 and 36 in push-pull relation.

The anodes 20 and 22 are excited by generated voltages of like phase. Grid 24 has a generated voltage of a phase which lags the voltage on the anode 20 by about 90 degrees so that tube 6 is in effect a variable inductance on the generator circuits. The voltage on the grid 26 is about 180 degrees out of phase with respect to the voltage on grid 24 and so leads the voltage on the anode 22 by about 90 degrees. Tube 8 is in effect a variable capacity in shunt to the generator. Differential control of the gain of tubes 6 and 8 increases the inductive and capacitive effects when the gain increases and vice versa to thereby control the tune of the generator in accordance with the modulating potentials.

In the push-pull reactance-tube circuits of my prior dockets one reactance tube received a 90 degree phase shift by means of a resistance-capacity phase shifter and the other reactance tube receives a 270 degree phase shift by means of a capacity-resistance phase shifter. In the modulator of the present application as described above like phase shifters are used for both reactance tubes, and the 180 degree phase difference between them is obtained by feeding the two phase shifters from opposite ends of the tuned circuit of the oscillator.

In Figure 1, tubes 6 and 8 are the reactance tubes and tube 4 is the oscillator. The reactance tubes are of the type which has an extra grid available for the application of the modulation. The modulation is applied to the extra grid and the phase-shifted feedback voltage is fed to the control grid. The phase shifter for tube 6 consists of resistance R and the grid-to-cathode capacity Cgk . C is a blocking condenser to keep the plate voltage off the control grid. The phase shifter for tube 8 consists of resistance R' and Cgk' . C' is likewise a blocking condenser. It will be noted that the phase shifter for tube 6

is fed from the plate side of tuned circuit 10 while the phase shifter for tube 8 is fed from the opposite end or grid side of the coil 38. Since the grounded point on the coil of tuned circuit 10 is at, or near, the middle of the coil, the voltage from one end to ground is 180 degrees out of phase with the voltage from the other end to ground. This 180 degrees effects the necessary phase reversal to cause reactance tube 8 to act as though its plate circuit were a shunt capacity. Since reactance tube 6 uses a phase shifter which causes its plate circuit to act as a shunt inductance, the two reactance tubes have opposite effects and, therefore, must be modulated in push-pull by push-pull transformer T.

Where the grounded point on the coil of tuned circuit 4 is not at the mid point of the coil, the feedback voltage for the two reactance tubes will not be balanced if the phase shifters employ identical elements. This unbalanced condition may be remedied by an adjustment of the relative magnitudes of resistors R and R' or condensers C_{gk} and C_{gk'}. For instance, in the case shown in Figure 1, the tap 40 on the coil 38 of tuned circuit 10 is offset towards the grid end of the coil 38. This tends to reduce the feedback voltage of reactance tube 8 as compared to reactance tube 6 when equal phase shifters are used. One method of rebalancing the feedbacks is to increase the value of resistance R; another is to increase the capacity of C_{gk} by adding external capacity. A still further method is to feed the phase shifter for tube 6 from a tap 42 on the coil 38 as shown in Figure 1a. In this case balance is attained by varying the position of tap 42.

Another method of applying the principle of this invention is shown in Figure 2. In this method the anodes 20 and 22 of the reactance tubes 6 and 8 are connected to opposite ends of the coil 38, but the grids 24 and 26 are both fed from the same end of the inductance 38. It is apparent, from this circuit, that reactance tube 6 has the proper phase shift to act as a shunt inductance, since the generated voltage on its grid lags the generated voltage on its anode about 90 degrees, while reactance tube 8 has a phase shift between its plate and grid circuits which is 180 degrees displaced from the relative phase shift obtained in tube 6. The generated voltage on the grid 26 of reactance tube 8 is the same as the generated voltage on the grid 24 and leads the voltage on the anode 22. This causes reactance tube 8 to act as a shunt capacity so that as in Figures 1 and 1a push-pull modulation is required from transformer T. In this circuit of Figure 2 a still further means of balancing the oscillator voltage fed to the two tubes is employed. In this modification the coil 38 of the oscillator circuit 10 is midtapped. This gives the proper balance for the reactance tubes, but introduces too much regeneration in the oscillator. This excess regeneration is compensated for by inverse feedback which is introduced by means of un bypassed cathode resistor R_k.

It will be apparent to those skilled in the art that tuned circuit 10 may consist of the tuned circuit of a push-pull amplifier. This amplifier then has its tuning modulated by the reactance tubes so that phase modulation of the carrier amplified by the amplifier is accomplished.

It will also be apparent that other types of phase shifters such as the resistance-inductance, RIL, type of Figure 3 and the capacity-

resistance, C2, R2, type of Figure 4 can be used for the phase shifters in the application of the principle of this invention.

Figure 3 is similar to Figure 2 in that the grids 24 and 26 are connected to the same point on the tank circuit 10 while the anodes 20 and 22 are connected to points at which the voltages are of substantially opposed phases. In this modification C and C' are again blocking condensers. The phase shifting reactances are RIL for tube 6 and RIL' for tube 8. In Figure 2 tube 6 acts as an effective inductance since the generated voltage on its grid 24 lags the generated voltage on its anode about 90 degrees. In Figure 3 phase shifters RIL cause the generated voltage on the grid 24 to lead the generated voltage on its anode 20 and as a consequence tube 6 in Figure 3 acts as a shunt capacity. The generated voltage in the grid 26 in Figure 3 is substantially the same as that on grid 4, and since the voltage on the anode 22 is about 180 degrees out of phase with respect to the voltage on the anode 20 the voltage on grid 26 lags the voltage on anode 22 and tube 8 acts as a shunt inductance.

The similarity between the arrangement of Figure 1 and the modification in Figure 4 will be apparent by inspection. In Figure 1 C and C' are blocking condensers. The phase shifters R and CgK cause tube 6 to act as a shunt inductance. In Figure 4 the phase shifting elements C2 and R2 are reversed so that tube 6 has a grid voltage which leads its anode voltage by about 90 degrees, so that tube 6 acts as a shunt capacity. In Figure 1 tube 8 acts as a shunt capacity. In Figure 4 the phase shifting elements C'2 and R'2 provide on the grid 26 a voltage which lags the generated voltage on the anode 22 and tube 8 acts as an effective inductance in shunt to the generator tank circuit 10.

In both of the modifications shown in Figures 3 and 4 the modulating potentials are applied in push-pull relation as pointed out in detail in connection with Figures 1, 1a and 2.

I claim:

1. In a wave length modulation system, a tuned circuit including inductance wherein high frequency wave energy the wave length of which is to be modulated flows, a pair of tubes each having an anode, a cathode and a control grid electrode, means coupling the anodes of said tubes to one end of said inductance, a connection between the cathodes of said tubes and a point on said inductance, phase shifting elements coupling the control grid of one of said tubes to a point intermediate the ends of said inductance, similar phase shifting elements coupling the control grid of the other of said tubes to one end of said inductance, and means for modulating the impedances of said tubes in phase opposition in accordance with signal.

2. Means for controlling the tuning of a circuit including an inductance wherein alternating current flows by controlling a reactive component of said circuit including, a pair of electron discharge devices each having an anode, a cathode, and a control grid, a connection tying said anodes together and coupling them to one terminal of said inductance, a coupling between the cathodes of said devices and a point on said inductance intermediate the terminals thereof whereby alternating current of like phase is impressed on the anodes of each of said devices, phase shifting elements coupling the control grid of one of said devices to a point on said in-

ductance intermediate the terminals thereof whereby alternating current is impressed on said control grid substantially in phase quadrature with respect to the alternating current on the anode of said one device, other phase shifting elements coupling one end of said inductance to the control grid of the other of said device to impress thereon alternating current in

substantially phase quadrature with respect to the alternating current on the anode of said other device, and means for differentially controlling the impedances of said device to thereby control the reactances produced therein which supplement the reactance of said first named circuit to control the tuning thereof.
